(57) **CLAIM**

The ornamental design for a portion of an overhead garage door façade, as shown and described.

DESCRIPTION

FIG. 1 is an elevational view of the portion of an overhead garage door façade shown in closed configuration; and, FIG. 2 is an elevational view of a portion of the design in FIG. 1 shown in partially open configuration.

The broken line showing of the simulated door jambs and the remainder of the garage door are for illustrative purposes only and form no part of the claimed design. The broken line showing of the garage building structure in FIGS. 1 and 2 and the vehicles shown in FIG. 2 are for illustrating an environment of the design and form no part of the claimed design.
